MACHINE GUARD

Henry Hackett, Selly Oak, Birmingham, and
Arthur Whittaker, Northfield, Birmingham,
England

Application June 15, 1931, Serial No. 544,564, and
in Great Britain June 24, 1930

4 Claims. (Cl. 192—132)

This invention relates to guards for machinery of the press type in which a reciprocatory part carrying one of a pair of tools co-operates with a stationary part carrying the other tool.

5 The object of the invention is to provide improved means for preventing injury to the hands of the operator while manipulating the work pieces which are placed between the tools. As is well known such machines are usually controlled 10 by a pedal operated clutch, and the risk is always present of the machine being set in motion before the hands of the operator are moved clear of the tools. Many forms of guards have been devised for protecting the operator. In machines for 15 stiffening the corners of cardboard boxes, to which our present invention particularly relates, a form of guard at present employed comprises a pair of hinged flaps which are arranged in combination with a stop adapted to control the clutch of the 20 machine, and also a cam which controls the flaps. Immediately after the machine has been started the cam allows the flaps to swing outwards away from the tools. If the operator's fingers are 25 encountered by the flaps either the fingers are moved clear of danger or the flaps are jammed by the fingers, in which latter case the stop which controls the clutch causes the clutch to be put out of action, and the further movement of the 30 slide is consequently arrested. Experience has proved that this form of guard is not entirely satisfactory. In the first place it is not completely reliable, and in the second place a region between the tools into which a finger can be and often is inserted is left entirely unprotected. By 35 the present invention the disadvantages of this form of guard are obviated in a simple and convenient manner.

The present invention comprises the combination with the reciprocatory part of the machine, 40 of an independently and freely slideable part which is adapted to surround the sides and front of the tools, and levers connecting the said part with a clutch stop and a controlling cam, the mode of operation of the guard being as hereinafter 45 described.

In the three accompanying sheets of explanatory drawings:—

Figure 1 is a front elevation, Figure 2 a side elevation, and Figure 3 a plan illustrating one application of our invention to a press of the kind employed as above described in the manufacture of cardboard boxes.

Figure 3a is a detail of a part of the arrangement shown in Figures 1 and 2.

55 Figure 4 is a sectional side elevation and Figure

5 a sectional end elevation illustrating the driving clutch of the press.

Figure 6 is a detail view of the clutch elements.

In carrying the invention into effect as shown, we secure to the front of the main guides *a* of the 60 machine a pair of additional guides *b* between which is mounted a freely movable gravity operated slide *A* consisting in part of bars *c* carrying at their lower ends suitably arranged guard pieces *d*. The guard pieces are disposed to lie along the 65 opposite sides of the reciprocatory tool *e* on the main slide of the machine, and in addition another guard piece *f* is arranged to lie across the front of the tools, this guard piece being carried adjustably on one or each of the other guard pieces. 70

Preferably the adjustment of the front guard piece *f* is made to depend on the adjustment of the lower fixed tool *g*. In the example shown in the drawings the lower fixed tool *g* is slideable horizontally on its supports *h* so that it can be 75 adjusted to any required position. This adjustment is effected by a lever *i* pivoted at its upper end to the machine frame and attached at its lower end to the tool *g*. Sliding of the tool from one position to another is effected by moving the lever. The work is supported on the front end of the tool *g* and the extent to which the tool projects beyond the supports *h* is varied to suit the size of the work pieces. When any 80 adjustment of the tool *g* is made it is also necessary to adjust the position of the guard piece *f* which moves over the front end of the tool *g*. To enable the adjustment of the guard *f* to be effected automatically the guard is carried by a block *j* movable in a slot in one side of the 85 adjacent part *d*. Also the block *j* is connected to the lever *i* by a rod *k*, so that movement of the lever for adjustment of the position of the tool *g* also causes a corresponding movement of the 90 guard piece *f*. 95

The freely movable guard slide is attached by means of a lever *l* to a spindle *m* to which are respectively secured a lever *n* co-operating with the periphery of a cam *o* on the main shaft *r* of the press, and a stop lever *p* which lies in 100 the path of a clutch controlling member *q*. The said member is a known device consisting of a thin plate as shown carried on a shaft *r*. This plate is provided with a projection *s* which in the position illustrated in Figure 5 is held by a lever *w* which is connected by a rod *x* with the usual 105 pedal of the press. On moving the rod *x* this lever is withdrawn for releasing the plate *q*. On release, the plate rotates and allows a clutch situated on the fly wheel *t* to engage the collar *u* 110

on the shaft and so transmit motion to the shaft. The clutch is put out of action by re-engaging the plate. The plate *q* and clutch form no part of the present invention as they are ordinary features of the machine illustrated in the drawings. Our invention is concerned only with the means whereby the plate *q* can be re-engaged after release by the pedal for stopping the machine, in the event of the operative's hand being in a dangerous position. To enable the action of the plate *q* to be more readily understood we have, however, illustrated the clutch in Figures 4 and 5. In one face of the fly wheel is secured a plate *y* formed with an annular groove *z* of uniform depth. In the adjacent face of the collar *u* is secured a plate 2 formed with an annular groove the base of which is of wavy configuration. Between the two plates are mounted a number of balls 3 or rollers which lie in holes in the plate *q*. A spring 4 bearing at one end against a stop 5 on the plate *q* and at the other end against a stop 6 on the collar *u* tends to move the plate *q* relatively to the collar *u*. This movement is resisted when the plate *q* is held by the lever *w*. On release of the plate *q* by the lever *w*, the plate first moves under the action of the spring 4 so as to cause the balls or rollers, by riding up the inclined surfaces in the plate 2, to press against the base of the groove in the plate *y*. A driving connection is thus set up between the fly wheel and the collar *u* on the shaft *r*, and motion is given to the shaft. After a complete revolution the projection *s* is again arrested by the lever *w* and this has the effect of releasing the clutch and stopping the machine. The plate *q* can also be held by engagement of the lever *p* with the projection *s*.

When the machine is at rest the guard occupies the upper position giving free access to the space between the tools. The first effect of depressing the starting pedal is to release the clutch controlling member *q* and set the machine in motion. During the initial movement of the machine the guard controlling cam *o* allows the guard slide to fall freely across the space between the tools. Preferably, the driving mechanism of the machine is so arranged that when the machine is at rest the upper tool does not occupy its upper position but is moved to such position during the initial part of the motion of the machine. Therefore, while the guard is falling freely across the tool space the upper tool is rising. Meanwhile, the clutch controlling member *q* is rotating towards the stop lever *p* connected with the guard. If the operator's hand is in a dangerous position it will either be pushed aside by the guard or it will be trapped by the guard, in which latter case the guard cannot complete its free movement, and the stop lever *p* will engage the projections *s* and arrest the clutch controlling member and so stop the machine. Only when the guard has reached the lower limit of its free movement is the stop lever *p* clear of the clutch controlling member. Consequently, an operative movement cannot be given to the upper tool until the guard has reached its lower position. If for any reason the guard is prevented from reaching its lower position the stop lever prevents the normal action of the machine.

Seeing that the guard surrounds the front as well as the sides of the tool it is impossible for the guard to complete its free downward movement if the hand of the operator occupies a dangerous position. It follows that by our present invention we are able to safeguard the operator

completely and in a manner which is free from mechanical complication or risk of defective operation of the guard.

Although the invention has been described in connection with cardboard box making machines it is not limited thereto and is applicable to other forms of presses. Also the invention is not limited to the example above described as subordinate mechanical details can be varied to meet different requirements. 80 85

Having thus described our invention, what we claim as new and desire to secure by Letters Patent is:—

1. In guards for machines comprising a reciprocating slide, a movable tool carried thereby, a fixed tool situated beneath the movable tool, a rotary shaft for reciprocating the slide, a fly wheel, a clutch for connecting and disconnecting the fly wheel and shaft, and a clutch controlling member which can rotate with the clutch and pedal operated means for controlling said member, the combination comprising a gravity operated slide arranged adjacent to the slide carrying the movable tool, guard pieces carried on the gravity operated slide and arranged to surround the sides and front of the movable tool, a controlling cam on the said rotary shaft, a subsidiary shaft arranged parallel with the said rotary shaft, and three levers on the subsidiary shaft, one of them being connected to the gravity slide, another being associated with the controlling cam, and the third being arranged to act on the clutch controlling member, as and for the purpose described. 90 95 100 105

2. In guards for machines having a fixed bed, a reciprocating part, a fixed tool carried by the bed, a movable tool for co-operating with the fixed tool carried by the reciprocating part, driving mechanism including a source of motion for imparting movement to the reciprocating part, a clutch for connecting and disconnecting the source of motion and the driving mechanism, a controlling member for the clutch, a lever engageable with said member, and pedal in direct connection with said lever, the combination comprising a gravity operated slide, guards carried by the slide and arranged in association with the movable tool, a controlling cam actuated by the driving mechanism of the reciprocating part, and three inter-connected levers, one of which is connected to the slide, another arranged to co-operate with the cam, whilst the third is arranged to engage the clutch controlling member of the machine when the guard is obstructed, substantially as described. 110 115 120 125

3. A guard mechanism for a clutch-controlled press having a rotary shaft, comprising a gravity operated guard slide, a lever connected to the slide for imparting lifting movement thereto, a cam on the rotary shaft, a second lever co-operating with the cam to control the movement of the first mentioned lever, and a third lever arranged to disengage the press clutch should the descent of the guard slide be obstructed, all of said levers being mounted in co-related arrangement on a single, rotatable, subsidiary shaft arranged parallel to 130 135 140 said rotary shaft.

4. A guard mechanism for a clutch-controlled press having a rotary shaft and movable and fixed tools, comprising a gravity operated guard slide carrying guard pieces on opposite sides of the 145 movable tool and also carrying an adjustable guard piece situated across the front of the movable tool, a lever connected to said slide for imparting lifting movement thereto, a cam on the rotary shaft, a second lever co-operating with the 150

cam to control the movement of the first mentioned lever, a third lever arranged to disengage the press clutch should the guard pieces be obstructed, all of said levers being mounted in co-related arrangement on a single rotatable subsidiary shaft arranged parallel to said rotary

shaft, and means connecting the adjustable guard piece with the fixed tool so that adjustments of the latter are accompanied by adjustments of the adjustable guard piece.
